UNITED STATES PATENT OFFICE.

EDWIN N. DENISON, OF WESTERLY, RHODE ISLAND.

DESIGN FOR A SPOON.

SPECIFICATION forming part of Design No. 21,422, dated March 22, 1892.

Application filed February 6, 1892. Serial No. 420,601. Term of patent 7 years.

To all whom it may concern:

Be it known that I, EDWIN N. DENISON, a citizen of the United States, residing at Westerly, in the county of Washington, in the State 5 of Rhode Island, have invented and produced a new and original Design for the Handles of Spoons, of which the following is a specification, reference being had to the accompanying drawing, forming a part thereof, which is 10 a face view of the spoon in which the design appears.

The leading features of my design consist in a spoon having a handle with a gracefully forked upper end, provided with the ornamentation hereinafter set forth.

15 A is the shank, and A' A² the forked upper end thereof.

B is the heart, having its lower end rounded and fitting within the fork.

C is a four-leaf clover partially superposed 20 upon the heart in the re-entering angle at the top. The edges may be smoothly rounded. The spoon-handle may be engraved or otherwise decorated on either or both its faces.

What I claim is--

25 The design for a spoon-handle, herein set forth.

EDWIN N. DENISON.
